UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 28,015, dated December 7, 1897.

Application filed October 23, 1897. Serial No. 656,240. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a description.

My invention relates to designs for prism-plates.

10 Figure 1 is a plan of a prism-plate embodying my design. Fig. 2 is a cross-section on line 2 2.

15 A is the body of the plate; B B, a series of surface areas thereon formed by the lines of separation C C. D D are prisms on the other side of the plate, and E E prisms in the va-

rious surface areas on the first-mentioned side of said plate.

The essential features of my design are found in a prism-plate comprising a substantially flat extended body with a series of prisms on one side thereof and a series of surface areas on the other side, formed by lines of separation, and prisms on such surface areas. 20 25

I claim—

A design for a prism-plate, substantially as shown and described.

FRANK L. WRIGHT.
